DESIGN FOR AN ELECTRIC IRON

Roy Opperman, Miamisburg, Ohio, assignor to
Sunmaster Products Corporation, Miamisburg,
Ohio, a corporation of Ohio

Application August 5, 1944, Serial No. 114,749

Term of patent 14 years

(Cl. D49—6)

To all whom it may concern:

Be it known that I, Roy Opperman, a resident of Miamisburg, in the county of Montgomery and State of Ohio, have invented a new, original, and ornamental Design for an Electric Iron, of which the following is a specification, reference being had to the accompanying drawings, forming part thereof, wherein:

Figure 1 is a side elevational view of an electric iron, showing my new design;

Figure 2 is an end elevational view of the elec-

tric iron as viewed from the right-hand end thereof with regard to Figure 1;

Figure 3 is a top plan view of the electric iron;

Figure 4 is a front elevational view of the electric iron as viewed from the left-hand end thereof with regard to Figure 1.

I claim:

The ornamental design for an electric iron, substantially as shown.

ROY OPPerman.
